Primary Examiner — Jonathan J Han(74) *Attorney, Agent, or Firm* — Banner & Witcoff, Ltd.(57) **CLAIM**

The ornamental design for a shoe, as shown and described.

DESCRIPTION

FIG. 1 is a bottom front perspective view of a shoe showing our new design;

FIG. 2 is a bottom view thereof;

FIG. 3 is a bottom opposite side front perspective view thereof;

FIG. 4 is a bottom rear perspective view thereof; and,

FIG. 5 is a bottom opposite side rear perspective view thereof.

The broken line showing of the chevron shaped regions form no part of the claimed design. The broken lines depicting the remainder of the shoe form no part of the claimed design.

1 Claim, 5 Drawing Sheets# US D979,200 S
